UNITED STATES PATENT OFFICE.

JAMES ALLINGHAM, OF CHICAGO, ILLINOIS.

ADJUSTABLE SUPPORT.

1,032,801.

Specification of Letters Patent. Patented July 16, 1912.

Application filed August 24, 1908. Serial No. 450,063.

To all whom it may concern:

Be it known that I, JAMES ALLINGHAM, a citizen of the United States, residing at Chicago, in the county of Cook and State of Illinois, have invented certain new and useful Improvements in Adjustable Supports, of which the following is a specification.

This invention relates to improvements in an adjustable support which may be used for various purposes, but it is more especially intended for a seat-carrying-bracket, and in the present instance I have shown it in the drawings and will hereinafter describe it as supporting such a bracket and in connection with a sink or similar vessel, to the end, that a convenient and comfortable seat may be afforded for the use of a person while using the sink in the performance of culinary or kitchen duties, such as washing or sorting berries, preparing vegetables, paring potatoes and fruit, and like work, or when using a wash-basin for toilet purposes, which seat, when not in use, may be turned on its support so as to occupy a position beneath the sink or vessel and out of the way.

The principal object of the invention is to provide a support of the above-named general character, which shall be attractive in appearance, strong, durable, efficient, and of such construction that its parts may be readily adjusted to suit certain conditions which may obtain by reason of the location thereof beneath the sink or vessel and near the wall of the room.

Another important object of the invention is to provide an adjustable support which shall be of such a nature that its manufacture will be greatly facilitated and the cost thereof diminished.

Numerous other objects and advantages of the invention will be disclosed in the subjoined description and explanation.

In order to enable others skilled in the art to which my invention pertains, to make and use the same, I will now proceed to describe it, referring to the accompanying drawings, in which—

Figure 1 is a view partly in section and partly in elevation of an adjustable support embodying one form of the invention, showing it connected to a wall or vertical support and in engagement with a portion of a sink

or other vessel, and illustrating a seat-carrying-bracket mounted on the support. In this view the sink and adjustable arm are 55 shown shortened for the convenience of illustration; Fig. 2 is a detached perspective view of the adjustable arm; Fig. 3 is a central vertical sectional view, showing a modification in the construction of the support, 60 and illustrating a portion of a seat bracket and a sink or vessel mounted thereon; Fig. 4 is an end view of the upper portion of the support; Fig. 5 is a plan view of a portion of the seat-bracket; and Fig. 6 is a view in 65 elevation of a core used in the manufacture of the body or main part of the support.

Like numerals of reference, refer to corresponding parts throughout the different views of the drawings.

70

The reference numeral 10 designates the body or main portion of the upright part of the support, which is preferably of the shape shown in the drawings and is mainly hollow, that is to say, it is provided with upper 75 and lower cavities 11 and 12, respectively, which are separated by means of a contracted and solid portion 13 just below an enlarged and partly spherical portion 14, which has at its upper portion a contracted 80 part 15 to form one of the bearings for the seat-bracket, as will be presently explained. The body 10 or main portion of the upright part of the support is preferably cast, and in order to avoid the cost and labor necessary 85 for drilling a hole through the solid portion 13 for the reception of the nipple 16 which has its lower portion screw-threaded, in the process of manufacture, I provide the nipple 16 with cores 17 and 18 to give the desired 90 shape to the cavities 11 and 12, and float said cores in the molding-flask to the end that when the sand cores are removed the nipple 16 will be securely held in position by means of the solid portion 13 of the body, which, as 95 shown, is provided at its upper end with diametrically disposed horizontal extensions 19 and 20, each of which is provided with a slot 21 for the reception of bolts 22 used for securing said extensions to depending lugs 23 100 with which some sinks are provided on their lower surfaces. The extension 19 is usually presented toward the front of the sink, and in order to hide the bolt 22 and nut thereon

said extension is preferably provided with a widened and vertically extended portion 24 (see Fig. 4) at its free end. Located in the lower portion of the body 10 is a tubular member or leg 25 which has in its upper end an internally screw-threaded coupling 26 to engage the screw-threaded portion of the nipple, and said member preferably has on its lower end an apertured base 27 which may be secured to the floor by means of screws or otherwise.

Located in the upper end of the body 10 is a cam-shaped washer 28 which, as shown in Fig. 1 of the drawings, is provided with a downwardly extending neck 29 to fit in the upper end of the body and with an overlapping top 30 which is tapered to rest on the top of the body and beneath the sink or vessel 31 which, as is well known, are sometimes inclined on their lower surfaces. Located between the top 30 of the washer 28 and the sink may be placed a piece of rubber, leather or other suitable material 32 to prevent the washer slipping. By using this washer it is apparent that, by adjusting the member 25 and the coupling 26 on the nipple 16 to the proper position, the upper portion of the body will be caused to firmly engage the bottom of the sink, and that as the washer 28 is beveled or cam-shaped it may be turned on the body portion 10 to the inclination of the sink. Secured to the wall or vertical support 33 to which the sink 31 may be secured and just below the latter is a horizontally extended bracket 34 which carries a screw-bolt 35 which is extended through a slot 36 in the adjustable arm 37 which is provided on its side edges with flanges 38 to form a guide-way for the bracket 34 so as to prevent lateral movement thereon of the arm. The outer end of the arm 37 is provided with one or more lugs or lateral extensions 39 to fit in the slot 21 of the extension 20 on the upper portion of the body 10 of the support. The outer end of the arm 37 is also provided with an opening 40 through which a bolt 41 may be passed for rigidly securing said end of the arm on said extension. Mounted on the reduced portions 13 and 15 of the body 10 are arms 42 and 43, respectively, of the seat-bracket 44, which has at its outer end a socket 45 to receive a projection 46 on one end of a section 47 of the seat-bracket, which section 45 has at its outer end a socket 48 to receive a projection 49 on the lower portion of the seat 50, which may be of the ordinary or any preferred construction. Each of the arms 42 and 43 of the seat-bracket 44 is made semi-circular in shape and is provided on each side of said circular portion with a transverse opening 51 to receive bolts 52 used for securing a semi-circular clip 53 on

each of said arms so as to pivotally mount the seat-bracket on the reduced portions 13 and 15 of the body 10 of the support, which portions, together with the enlargement 14, will form bearings for said arms so as to permit the bracket to be turned to any suitable position. By providing the outer portion of the part 44 of the seat-bracket with a socket and the section 47 and seat 50 with projections 46 and 49, respectively, of corresponding shape to fit in said socket, it is apparent that the seat and section 47 can be interchangeably used on the portion 44, but by using the section 47 it is evident that the seat may be arranged at any desired angle with respect to the portion 44 of the seat-bracket.

From the foregoing and by reference to the drawings it will be readily understood and clearly seen that as the adjustable members, that is, the nipple 16, leg or member 25 and coupling 26, are located within the body member 10, which may be of any ornamental design or shape, but preferably of that shown in the drawings, none of the means for adjusting the support vertically or longitudinally will be disclosed, and that a support attractive in appearance will be presented. Furthermore, it is apparent that the adjustable arm and bracket 34, as well as the means for connecting the upper portion of the body member to the sink shown in either Figs. 1 or 3, will serve to hold the body and its adjustable leg or member in an upright position against the weight which may be placed on the seat-bracket.

It will also be obvious from the foregoing description and disclosure of the improved adjustable support that it is susceptible of considerable modification or variations in the details of construction without material departure from the principles and spirit of the invention, and for this reason I do not wish to be understood as limiting myself to the exact construction shown and described in carrying out my invention in practice.

Having thus fully described my invention, what I claim as new, and desire to secure by Letters-Patent, is—

1. The combination with an upright support provided at its upper portion with a horizontally projected extension provided with a laterally and longitudinally disposed slot, of a suitably supported horizontal bracket having a vertical projection on one of its surfaces, an arm adjustably secured to said bracket near one of its ends and having a horizontally disposed longitudinal slot to receive said projection, and laterally disposed means near its other end to fit in and engage the slot of the said extension.

2. The combination with an upright support provided at its upper outer portion

with a horizontally projected extension provided with a laterally disposed slot, of a horizontal bracket suitably supported near the upper portion of said support, an arm secured to said bracket and having a guideway therefor, said arm also having lateral extensions to fit in the slot of the extension

on the support, and means to secure said arm to said extension.

JAMES ALLINGHAM.
